CAMPING ACCESSORY

Arthur B. Butterworth, Newport News, Va.

Application August 11, 1950, Serial No. 178,949

6 Claims. (Cl. 5—113)

1

This invention relates to a camping accessory and more particularly to an apparatus for providing an enclosure for a camp cot.

In the past it has been necessary, when camping outdoors, to sleep on the ground in a sleeping bag or the like when only a small tent was available. It is possible, of course, to sleep on beds or cots if a substantially-sized tent is available, but a tent large enough to contain one or two beds is quite bulky, as well as expensive. When traveling by automobile, it is possible to sleep in the vehicle, particularly if it is especially constructed for such use; however, this is not particularly comfortable and is limited to areas to which the automobile can be driven.

The applicant has devised an apparatus whereby the camper may sleep on his camp cot and yet enjoy all the benefits of being within a tent; that is, he will be safe from rain and storm, will be clear of the ground, and will be surrounded by an enclosure from which mosquitoes and the like may be excluded.

Furthermore, the applicant has provided for an apparatus of the kind described that is both light and inexpensive because of the small amount of material used in its fabrication. The lightness is particularly important to campers with whom weight is always a handicap.

Another important feature of the applicant's device is its ease of assembly. When, as is often the case, the camper must set up his sleeping accommodations in the dark, it is imperative that the apparatus be simple. Furthermore, when the camper is tired or when a storm is coming up, the applicant's device is particularly useful, since it may be set up in a very short time.

Among the other desirable features incorporated into the applicant's device are its strong construction, its adaptability to fabrication by mass production procedures, and the attractiveness of its appearance.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

The character of the invention, however, may be best understood by reference to certain of its structural forms, as illustrated by the accompanying drawings in which:

2

Figure 1 shows the camping accessory of the instant invention attached to a camp cot and viewed in the direction of the end of the cot.

Figure 2 shows the framework of the present invention as attached to a cot viewed in the direction of the side thereof and with portions of the cot and accessory broken away.

Figure 3 shows a detail of a part of the accessory of the invention.

10 Figure 4 shows a modification of the camping accessory of the invention shown in use with two camping cots and viewed in the direction of the ends of the cots.

Figure 5 is a sectional view of the modification 15 illustrated in Figure 4 taken on line 5—5 and looking in the direction of the arrows.

In Figures 1 and 2 the accessory, generally designated 10, is shown attached to and in use with a camp cot 11. The accessory 10 comprises 20 end members 12, a ridge pole 13, and a cover 14. The cot 11 is of a commonly used type and consists of stringers 15, and transverse members 16, presumably supporting springs (not shown) on which rests a mattress 17, legs 18 being attached to the stringers 15. The end members 12 are of generally semi-circular shape and are provided centrally with a window 19 which usually has an insert of mosquito netting, but, of course, any desired material may be used. This window 19 is for the purpose of admitting air and light into the enclosure. The bottom, diametric edge of the end member 12 is formed with notches 20, as best shown in Figure 3, for a purpose to be described later. The end members are 25 made of thin, light material, such as plywood. The end members are held in a vertical position against the outside, vertical surface of the transverse members 16 of the cot 11; for this purpose carriage bolts 21 are passed through the transverse members 16, the end members 12 are 30 placed on the bolts so that the bolts lie in the notches 20, a clamping bar 22 is passed over the bolts and the assembly is held together by wing nuts 23. From this it can be observed that the bolts 21, the clamping bars 22, and the wing nuts 23 remain with the cot during periods of non-use. Also, it should be noted that the end members 12 can be inserted between the transverse member 16 and the clamping bar 22 without taking the bar 22 or the nut 23 from the bolt 21; the saving in time is obvious. The ridge pole 13 extends from the highest medial point of one end member to the same point of the other end member; pole and end member are joined by 35 the use of mutual notches, the details of which are not shown. The ridge pole 13 lends rigidity

to the structure and acts to prevent sag in the cover 14. The cover 14 is of generally rectangular shape, having a length about the same as the distance from end member to end member and a width equal to the arcuate portion of the periphery of an end member. The corners of the rectangular cover as well as intermediate points on the sides are provided with loops 24 of rope, leather, or canvas for a purpose to be explained later. In addition, the ends of the rectangular cover 14 are provided with a wide, auxiliary hem 25, open at the ends, through which passes a rope 26.

In setting up the applicant's invention, the two end members 12 are clamped to the cot, as has been described, and the ridge pole 13 is fastened in place. Then, the cover is laid over the end members and the ridge pole and the loops are tied down; this may be done by passing them over buttons 27 on the inside surface of the stringers 15 of the cot, or they may be passed over stakes in the manner shown in conjunction with the modification in Figure 4. Then, the ends of the rope 26 are pulled toward the center of the end members 12, thus tightening up the cover, and are then tied. Leaving a loop 24 at the head of the cot unfastened until the camper is in the enclosure provides a means of access that is large enough to be practical; this is particularly true if the cover be made so that the hem 25 does not come down all the way to the cot, or, in other words, is less than co-extensive with the ends of the cover along which it lies.

Figure 4 shows a modification of the applicant's invention which provides sleeping facilities for two persons. In general, the arrangement is much the same as the device shown in Figure 1 and described above and makes use of the same inventive concept. In this arrangement, the accessory of the applicant is shown attached to cots 11. An end member 12 is attached to the transverse member 16 of each of the beds by means of clamping bars 22 and bolts and wing nuts 23. Each of the end members 12 is of semi-circular shape and has a window 19 and a ridge pole, shown in dotted lines. In addition, the arrangement is provided with auxiliary posts 30 and ridge pole 31, the posts and pole being attached together by a detachable means, such as mating notches. The posts 30 are clamped in a vertical position between the ends of the clamping bars 22 in a manner best shown in Figure 5; angle irons 32 are fastened to the outer vertical surfaces of the clamping bars 22 and a bolt 33 having a wing nut 34 passes through apertures in the free flanges of the angle irons 32; tightening the nut 34 will, of course, clamp the post 30 in position. Once the framework has been set up in the manner just described, the enclosure is completed by the use of covers 35 and 36. These covers are exact counterparts of the cover 14 described above, in that they are of generally rectangular configuration with hems 37 and 38, respectively, attached to their end portions, ropes 39 and 40 running through the hems, and loops 24 attached to the corners and intermediate portions of the sides. The cover 35 is laid across the end members 12, and the ridge poles and extends from point A to point C; one end of its rope 39 is attached to a cleat 41 on clamp bar 22. The cover 36 extends from point D to point B and one end of its rope 40 is attached to cleat 42 on a clamping bar 22. The other ends of the ropes are pulled toward the middle and tied together in the vicinity of the post 30. Of course, one of the covers overlaps the

other from point B to point C; in the drawing, cover 36 is shown as overlapping cover 35. In addition, a filler member 43, having a hem along its edge as shown, is used to cover the space between the end members 12 and the covers 35 and 36; the filler member 43 is held fixed at the top between the covers and the end members 12 and ridge pole 31 by the inward pressure of the covers created when the ropes 39 and 40 are drawn taut and knotted; at the bottom the filler member 43 is held in juxtaposition to the end members 12 by ropes 44 and 45 which are attached to cleats 46 and 47 on the clamp bars 22.

Among the possible variations of the above-recited specific embodiments is that where the embodiment shown in Figure 4 is practiced by using a single, large cover instead of two, small covers. It is possible also to use a cover of that type where the filler member is integral with the cover.

Having thus described my invention, what I claim as new and desire to secure by Letters Patent is:

- 25 1. The combination of two camping cots in side-by-side relation and an accessory therefor comprising end members of semi-circular shape formed of stiff sheet material and clamped at their diametrical portions in a vertical position to the ends of each of the cots, the two cots being held in juxtaposition by clamping means, vertical posts held between the ends of the cots by actuation of said clamping means, a ridge pole joining the tops of the posts, a flexible cover of rectangular conformation stretched over the end members and the ridge pole and held there to form a sleeping closure.
- 30 2. The combination of two camping cots in side-by-side relation and an accessory therefor comprising end members of semi-circular shape formed of stiff sheet material and clamped at their diametrical portions in a vertical position to the ends of each of the cots, each end member being provided with a centrally-located window, a ridge pole joining the top portions of the end members on each cot, the two cots being held in juxtaposition by clamping means, vertical posts held between the ends of the cots by actuation of said clamping means, a ridge pole joining the tops of the posts, a flexible cover of rectangular conformation having loops at the corners stretched over the end members and the ridge poles and held there by the loops to form a sleeping enclosure.
- 35 3. A camping accessory comprising a cot, an end member made of a thin board material and formed in a semi-circular shape, bolts running outwardly from the transverse end members of the cot, a clamping bar and wing nuts on the outer, threaded ends of said bolts, notches in the diametric edge of said end member, said end member being clamped between the transverse member of said cot and said clamping bar by the action of the nuts and bolts and lying therebetween with the bolts residing in said notches.

- 40 4. A camping accessory comprising a cot, end members of semi-circular shape formed of stiff sheet material and clamped at their diametrical portions in a vertical position to the ends of the cot, each end member being provided with a centrally-located window, a ridge pole joining the top portions of the end members, a flexible cover of rectangular configuration having loops at the corners stretched over the end members 75 and the ridge pole and held there by the loops

to form a sleeping enclosure, bolts extending outwardly from the ends of the cot, notches in the diametric edges of the end members, a clamping means on the outer ends of the bolts, the said end members being clamped between the ends of the cot and the clamping means with the bolts residing in the said notches.

5. The combination of two camping cots in side-by-side relation and an accessory therefor comprising end members of semi-circular shape formed of stiff sheet material and clamped at their diametrical portions in a vertical position to the ends of each of the cots, the two cots being held in juxtaposition by clamping means, vertical posts held between the ends of the cots by actuation of said clamping means, a ridge pole joining the tops of the posts, a flexible cover of rectangular conformation stretched over the end members and the ridge pole and held there to form a sleeping enclosure, bolts extending outwardly from the ends of the cots, notches in the diametrical portions of the end members, a clamping means on the outer ends of the bolts, the said end members being clamped between the ends of the cot and the last-named clamping means with the bolts residing in the said notches.

6. The combination of two camping cots in side-by-side relation and an accessory therefor comprising end members of semi-circular shape

formed of stiff sheet material and clamped at their diametrical portions in a vertical position to the ends of each of the cots, each end member being provided with a centrally-located window, a ridge pole joining the top portions of the end members on each cot, the two cots being held in juxtaposition by clamping means, vertical posts held between the ends of the cots by actuation of said clamping means, a ridge pole joining the tops of the posts, a flexible cover of rectangular conformation having loops at the corners stretched over the end members and the ridge poles and held there by the loops to form a sleeping enclosure, bolts extending outwardly from the ends of the cots, notches in the diametrical portions of the end members, a clamping means on the outer ends of the bolts, the said end members being clamped between the ends of the cots and the last-named clamping means with the bolts residing in the said notches.
